UNITED STATES PATENT OFFICE.

JOHN M. HARTMAN, OF PHILADELPHIA, PENNSYLVANIA.

METHOD OF PREVENTING CHILLING OF BLAST-FURNACES.

SPECIFICATION forming part of Letters Patent No. 292,305, dated January 22, 1884.

Application filed October 17, 1883. (No model.)

To all whom it may concern:

Be it known that I, JOHN M. HARTMAN, of the city and county of Philadelphia, in the State of Pennsylvania, have invented a certain new and useful Method of Preventing the Chilling of Blast-Furnaces through the Accumulation of Cinder in the Vicinity of the Tuyeres.

The following is a specification of my invention, the accompanying drawing serving to illustrate the nature of the difficulty to be remedied and the mode of operation which I pursue in order to obviate it.

It is well known that one of the most usual and most troublesome causes of chilling in furnaces is the accumulation of cinder opposite to the tuyeres. When a furnace is working properly, the contents of the interior at this point and for some distance above are entirely composed of the burning coal or other fuel—a condition of affairs which not only effects the reduction of the ore above, but maintains the iron and cinder in the crucible below the tuyeres at the proper melting temperature.

If, by inattention, the cinder is permitted to accumulate until it reaches the tuyeres, a chilling at once takes place in front of the tuyere, as the temperature of the entering blast is not usually over 1200°, while the melting-point of the cinder is about 3500°. This chilling of the cinder soon forms a shell or coating opposite to the tuyeres impervious to the blast, so that the latter is prevented from reaching the coals and maintaining the combustion at the tuyeres.

The blast then tends to force its way up the side of the furnace, and the chilling of the cinder may continue upward until a shell or roof thereof is formed above the tuyere and the latter becomes entirely inefficient for supplying air. Moreover, the tending of this direction of the blast is to burn away the wall above the tuyere and endanger the furnace. It is not practicable to break or pierce this shell of hardened cinder by means of bars or tools, as

the heat is sufficient to soften them, and they bend up when applied, so that the furnace frequently remains for days or weeks in an impaired condition, until, by forcing or otherwise manipulating the blast and using a large amount of extra coal, the cinder has become melted and worked away from the tuyeres.

In some instances furnaces have been shut down and apertures dug into the bottom for the removal of the cinder bodily, and such excavation has been aided by blasting with explosives, but of course with the attendant loss of time from the stopping of the furnace, and with the further disadvantage that the chilling continues in a constantly-increasing ratio from the air-supply being cut off.

I have discovered that by the use of a small torpedo or other explosive inserted through and fired in the immediate vicinity of the tuyere, cracks or orifices can be readily made in the cinder shell, through which the air-blast can penetrate, such operation being conducted without stopping the furnace. The torpedo should of course be applied as soon as the presence of the cinder at the point becomes manifest, this fact being readily determinable by examination through the tuyere. This method of opening air-passages into the interior of the furnace has the further advantage that, instead of further cooling the furnace, (as the opening or excavation to remove the cinder necessarily does,) it starts combustion and generates heat just at the point where an increase is needed.

In the accompanying drawing I have illustrated, by a view in vertical section through a furnace, the mode of operation above specified for my invention. The furnace shown contains features of construction which will form the subject of a separate application, and which consequently are not described herein.

A is the wall of the furnace; B, the tuyere, and C the stock within the furnace.

D represents a shell or ledge of chilled cinder in the form and position frequently found to exist, and extending for some distance upward from the tuyere-orifice. Under these conditions the tendency of the blast is to work up between this cinder shell and the wall of the furnace, leaving a central core of stock.

The torpedo E should be inserted through the tuyere B, preferably by means of a heavy bar, F, which acts in measure as a tamper, and the torpedo, being forced into the cinder shell at a point opposite to the tuyere, is then exploded. The result of the explosion is to open fissures or cracks in the shell, allowing the blast to pass through the shell into the in-

terior of the furnace, re-establishing the combustion at the tuyeres and soon melting the remaining portions of the cinder.

I prefer to construct the torpedo of a stout wooden case or shell holding a sufficient quantity of giant-powder or other explosive, and having a proper fuse attachment for firing. The amount of explosive required will of course vary with the extent and thickness of the cinder shell formed; but ordinarily, if the operation is timely, a very small charge—say two ounces—of giant-powder will suffice, since the object is not to blast out or remove the cinder, but merely to open cracks therein and permit the entrance of the air-blast.

I claim—

The hereinbefore-described method of preventing the chilling of blast-furnaces through the formation of cinder shells, and of restoring the blast-circulation therein by exploding a torpedo at a point opposite to the tuyere and in juxtaposition to the cinder shell, and immediately forcing the blast through the fissures formed by such explosion.

JOHN M. HARTMAN.
